DEMOUNTABLE ELECTRON TUBE

Louis A. Gebhard, Washington, D. C.

Application March 14, 1933, Serial No. 660,707

16 Claims. (Cl. 250—27.5)

(Granted under the act of March 3, 1883, as
amended April 30, 1928; 370 O. G. 757)

My invention relates broadly to electron tubes and more particularly to a construction of demountable electron tube in which the parts thereof may be readily disassembled for repair, 5 and defective parts replaced and the parts assembled and the tube again placed in operation.

One of the objects of my invention is to provide a construction of demountable electron tube having means for readily disassembling parts of 10 the tube to enable parts of the tube to be renewed from time to time and the tube reassembled and evacuated for continued operation.

Another object of my invention is to provide a construction of high power tube having means 15 for replacing the heater element of the tube when the heater element has deteriorated during operation of the tube.

Still another object of my invention is to provide a construction of demountable electron tube having means for compensating for thermal expansion of the cathode under conditions of 20 operation of the tube.

A further object of my invention is to provide a fluid cooled anode structure for a demountable electron tube having means for insuring an air tight assembly of the elements 25 within the tube for evacuation from time to time for maintaining the required degree of vacuum.

Other and further objects of my invention reside in a construction of demountable electron tube having electrodes of a construction which will readily permit assembly and disassembly of the parts of the tube for replacement of defective parts as will be set forth more fully in the specification hereinafter following by reference to the accompanying drawings, in which:

Figure 1 is a side elevation of an electron tube constructed in accordance with my invention; Fig. 2 is a central, vertical, longitudinal section thereof; Fig. 3 is a sectional view of a portion of the upper end of the tube showing more particularly the chuck for holding the upper end of the filament and the means employed for cooling the same; Fig. 4 is a similar view showing the chuck employed for holding the lower end of the filament and the means for cooling the same; Fig. 5 is a sectional view showing more particularly the mounting the grid; Fig. 6 is a horizontal sectional view taken on line 6—6 of Fig. 5; Fig. 7 is a top plan view of the tube complete; Fig. 8 is a horizontal sectional view on an enlarged scale taken on line 8—8 of Fig. 1; Fig. 9 is a horizontal section taken on line 9—9 of Fig. 4; Fig. 10 is a similar view taken on line 10—10 of Fig. 4; Figs. 11, 12, and 13 illustrate modified

forms of gas tight joints which may be used for insuring a gas tight closure within the tube of my invention; and Fig. 14 illustrates a schematic form of insulated binding device which may be used in compressing the end plates with respect to the ends of the insulated sleeves which are secured over the tubular anode structure.

My invention is directed to a construction of electron tube which may be assembled and disassembled with ordinary tools. This is of great 10 value from an economical standpoint in that the heater element, cathode or filament, may be replaced very easily and at low cost. In tubes of the ordinary type of construction, after the filament is burned out or the tube seriously injured, 15 the whole tube is discarded. In the demountable tube described herein, only the damaged part or element need be replaced. Thus the cost of operation of a radio transmitter or other apparatus using these tubes is greatly reduced. 20

Referring to the drawings in detail, filament 1 consists of a single wire passing through the center of the tube. The use of a single wire filament permits smaller diameter of the plate and grid structures, resulting in a more compact tube 25 with smaller inter-element capacities. It also permits the end plates of the tubes to be the filament terminals, thus reducing the number of insulated air tight joints in the tube to a minimum. The ends of filament 1 are held in chucks 30 2 and 3. Chuck 2 is secured to a corrugated metal disc mounted on end plate 5. Chuck 3 is mounted directly on end plate 6. A grid 7 of cylindrical shape is also supported from end plate 6 by means of insulator 8 and insulated rod 35 44 which incidentally forms the grid terminal of the tube. The insulating bushing 9 surrounds rod 44 and insulates it from end plate 6. The anode of cylindrical shape is shown at 10 supported between insulating members 11 and 12 40 which are also of cylindrical shape. The tube is held together by means of longitudinal insulating rods 13 extending through the end plates 5 and 6, fastened by means of bolts 14 as shown in Fig. 2. Clearance is provided as shown at 15 45 between end plate 6 and insulating members 13 so that the joints may be properly drawn to make them air tight.

Figs. 3 and 4 show the structure of the chucks 2 and 3 holding the filament 1. The chucks consist of a body portion 15 having a plurality of outwardly extending jaws, slotted at 16 and formed with an appropriate recess 16b confining the end of filament 1. The ferrule 17 has an internal conical surface which engages with a correspond- 50 55

ing conical surface on the chuck faces forming the extremity of the body portion 15 and which causes tightening of the filament in the chuck when the encircling ferrule 17 is screwed home 5 on body portion 15. To permit the turning of the ferrule its outer surface is preferably knurled or arranged to take a wrench. The means of fastening the two chucks to the end plates differ. Fig. 3 shows the mounting on one end and 10 Fig. 4 the mounting on the other end of the filament. The mounting shown in Fig. 3 provides a means of taking up the expansion of the filament due to the increase in temperature when heated. The member 15 has a shoulder 18 15 which is appropriately fastened to the corrugated disc 4 by welding, brazing or soldering. This makes an air tight joint. The air tight joint between 4 and 5 is made with the aid of gasket 20, ring 21 and screws 22. The tension on the filament 1 due to disc 4 is augmented by the use 20 of a pair of flat springs 23 fastened with screws 22 and engaging with a second integral shoulder 24 on the body portion 15, tending to urge the same upward, as clearly shown in Fig. 3.

25 The lower filament chuck shown in Fig. 4 is stationary. An air tight joint with an end plate 6 is accomplished through the use of a gasket 24 between the shoulder 18 on member 15 and end plate 6. The joint is tightened by a nut 30 threaded on the body portion 15. Reference character 26 designates another gasket interposed between the nut 25 and end plate 6. Both filament chucks are cooled by the passing of a suitable cooling fluid through a cavity 27 formed inside 35 the body portions 15. The cooling fluid enters through insulating tube 28 passing through metal tube 30 and is ejected against the surface of the cavity 27 adjacent to the filament 1, which is the hottest surface. The liquid then passes out 40 through metal tube 29 and insulating tube 31. The metal tubes 29 and 30 are supported from the body portion 15 by means of a plate 32 mounted at the end of chamber 27. (See more 45 particularly Fig. 9.) The cavity 27 is tapered toward the filament 1 so as to permit greater thickness of the body portion 15 at this point. The body portion 15 thus has greater thermal conductivity and strength and there is less liability of an air leak at this point. Better cooling 50 of the chuck and adjacent parts is also obtained. Tube 30 is bent so that the center of its inner end coincides with the axis of 15, (see Figs. 3 and 4).

55 If the filament is burned out or injured it may be replaced by removing the chucks 2 and 3 from the tube. The chuck 2 may be removed by taking out screws 22 and lifting out the chuck. After chuck 2 has been removed chuck 3 may be taken out of the tube by loosening nut 25, pulling chuck 60 3 up through grid 7 and out through the hole in end plate 5. The old filament may be taken out of the chucks by loosening the ferrules 17. In inserting a new filament the exact length is obtained by the use of a jig into which the chucks 65 are placed. After the chucks have been tightened, the unit is placed inside the tube, the lower end passing through the aperture in end plate 5. The joint at the upper end plate 5 is completed first and then the lower end plate 6 is tightened by nut 25. The jig used in adjusting the length of filament is ganged so that with the filament cold it will be just a little short for the tube. Then when nut 25 is tightened, corrugated disc 19 is pulled down. Disc 19 tends to react 70 against this pull with a spring action augmented

by the pair of flat spring arms 23. When the filament becomes hot, it expands and this expansion is taken up by means of the disc 19 and spring arms 23. Thus the filament is always kept taut and central with respect to the tube. 5 The body member 15 of chuck 3 has flattened sides where it passes through 6 to prevent its turning when the nut 25 is tightened, and thus torsional strains in the filament are prevented. The jig used in adjusting the filament is ganged 10 so that the proper adjustment of the flattened portions on 15 of chuck 3 and the apertures in disc 19 through which screws 22 pass, is maintained. The filament terminals are shown at 33 and 34 connected respectively to end plates 5 15 and 6.

Fig. 5 shows a side elevation of the lower end of the grid structure 7 and its terminal. The grid consists of a wire spiral 35 welded to upright rods 36 which are in turn supported by and welded 20 to cylindrical members 37 and 38. Member 38 has laterally extending feet 39 and 40 at its lower end which serve to support the grid structure. The foot 39 is fastened to insulator 8 by means of screw 42. Insulator 8 is fastened to end plate 25 6 by means of stud 43. The stud 43 does not pass entirely through end plate 6 thus avoiding the troubles of another air tight joint projection. The foot 40 is fastened to rod 44 between a washer 45 and a nut 46. Rod 44 passes through insulat- 30 ing bushing 9 which projects through end plate 6. A cylindrical insulating member 47 passes over the bushing 9 on the outer side of the end plate 6. Member 48, together with nuts 49, permits tightening to make air tight the joints 35 formed with the use of gaskets 50 and 51. The bushing 9 preferably has a shoulder 9a which engages gasket 51. The joints between anode 10 and insulating members 11 and 12 are made 40 air tight by the use of gaskets 52 and 53, being of appropriate cross section. Shoulders 54 and 55 are provided on anode 10 to make the joint. A fillet 56 is provided at the base of the shoulder for added strength. To these shoulders is secured 45 a cylindrical member 57 which provides a jacket around the anode 10 in which cooling fluid may circulate. Inlets 59 at opposite ends of the chamber 70, thus formed, and an outlet 61 are provided for this chamber. This arrangement provides cooling for the joints between anode 10 50 and insulators 11 and 12. The cooling fluid passes to portions of the anode adjacent to these joints first and thus provides maximum cooling. An anode terminal is shown at 63.

The ends of anode 10 are arranged to extend 55 beyond the shoulders 54 and 55 and inside insulating members 12 and 11. A clearance space 62 is provided between the inside of these insulating members and the anode 10. This arrangement has a number of advantages. The clearance inside the tube between the anode 10 and end plates 5 and 6 can be made small thus making maximum use of the electron discharge from the filament. The grid, being mounted on end plate 6, does not interfere seriously with the extension of the anode. The surface leakage path over the insulation is long both inside and outside the tube. The clearance on the outside of the tube between anode 10 and end plates 5 and 6 is large as it has to be in air. The clearance 65 on the inside can be small on account of the evacuation of the tube. The insulating material is placed in a weak part of the electric field and thus the strains in it are a minimum. By the use of a cylindrical shape for insulators 11 70 75

and 12 these can easily be made and the ends ground to give a good air tight joint. The extremities of anode 10 are preferably rounded to increase the break-down voltage. The joints between end plates 5 and 6 and insulators 11 and 12 are made similar to those between the anode 10 and these insulators. The joints may be fluid cooled by providing members on end plates 5 and 6 adjacent to these joints and passing a cooling fluid through these chambers. The insulating material used to make up the insulators is preferably magnesium silicate or a combination of aluminum and magnesium silicates properly heat treated. The use of these materials gives low losses at radio frequencies. A further advantage is that the material is nonporous, preventing leakage of air into the tube. This is due to the fact that contiguous cells of the material are not connecting and are of very close texture. This structure also permits a good joint between a ground surface and the gasket such as is used at the ends of the insulators 11 and 12. Further precaution against leakage is provided by glazing both the inside and outside of the insulators. The glazing adds to the protection of the insulation against accumulation of dirt in handling. It also prevents impairment of the insulation inside of the tube due to electron emission. A connection to an exhaust pump is provided at 64 from the interior of the tube. The tube is evacuated by the exhaust pump and the required vacuum automatically maintained by suitable pressure controlled mechanism. If desired, the tube may be mounted on top of the exhaust pump with suitable supports.

In addition to the advantages heretofore described in the use of the single filament there are many others. To obtain the same electron emission from a single filament as for multiple filaments, it is necessary to use a diameter with the same length which will provide equal area. This means a larger diameter filament and one which will be more rugged. No more power will be required to maintain it at the same temperature for the same emission. The current through the filament will be greater and the voltage drop less. The ratio between the filament current and plate current will be greater and, therefore, the change in heating of the filament due to passage through it of the plate current will be less. Thus the chances for localized heating are reduced to a minimum and a more reliable tube obtained.

The tube of my invention may be disassembled very easily for inspection of parts and replacement of those parts which are defective. One of the outstanding advantages of the design is that the filaments may be replaced without disassembling the tube, and in a very short time. The tube need not even be removed from the pump or from connection with the pump to do this. The plate and grid structures remain intact. All that need be removed are the filament chucks. The grid structure, being supported from the end plate, is readily aligned with respect to the filament and anode.

Throughout the several assembly views of the tube of my invention, I have illustrated gaskets at each of the joints which are placed under compression for preventing the leakage of gas. To simplify the illustration of the invention, these gaskets have been illustrated schematically in the assembly views. However, I desire that it be understood that in practice the joints are formed with coacting faces establishing a serpentine course through the joint which substantially pre-

vents undesirable leakage and provides a gas tight seal.

Fig. 11 shows end plate 5 provided with an annular projection 5a which fits into a coacting annular recess 11a in the insulator 11. The gasket 53 which is disposed therebetween, provides a substantial seal against the leakage of gas. Fig. 12 shows a modified construction in which end plate 5 is provided with a pair of concentric ribs depending from end plate 5, as illustrated at 5b and 5c. These ribs fit into coacting annular recesses 11b and 11c in insulator 11. The gasket 53 which is disposed between the ribs and the coacting recesses is deformed out of plane for establishing a gas tight seal. Fig. 13 shows a further modified form of seal in which end plate 5 has an annular projection 5d thereon having an echelon or offset annular face. The insulator 11 is provided with a coacting face which is offset in steps or echelon formation, as represented at 11d. The gasket 53, disposed between the echelon faces 5d and 11d, serves to prevent seepage of gas between the joints. As I have pointed out, any one of the types of joint illustrated, or any other form of joint may be used for insuring a gas tight closure within the anode structure.

It will also be understood that the tension members 13 have been illustrated substantially for the purpose of simplifying the illustrations and that in practice, I employ any suitable arrangement of tension adjusting means for compressing the end plates 5 and 6 against the gaskets 52, insulator 11, gaskets 53 and insulator 12, and against the ends of the anode. One form of tension adjusting means has been illustrated in Fig. 14.

A rod 65 of insulating material such as magnesium silicate or a combination of aluminum and magnesium silicate properly heat treated is employed for maintaining the parts of the tube in assembled relation. I have found that these materials possess high insulating properties and can be machined. Threads 65a are cut on one end of rod 65 and the rod engaged in end plate 6. Threads 65b are cut on the opposite end of rod 65 and are engaged by nut 66, which bears against end plate 5 enabling the end plate to be compressed against the gasket and anode assembly.

Various other forms of tension means may be employed, and I do not intend my invention to be limited to the particular forms shown.

By reason of the fluid cooling of the chucks which support the replaceable filament and the fluid cooling of the anode in the tube structure of my invention, a high degree of efficiency may be obtained throughout the operating life of the tube. The structure of the tube is such that the joints which must be maintained airtight are restricted thereby avoiding loss of vacuum. The parts of the tube are readily replaceable and are so simplified in their construction that the total cost of the tube is held quite low.

While I have described the tube of my invention in one of its preferred embodiments, I desire that it be understood that modifications may be made and that no limitations upon my invention are intended other than are imposed by the scope of the appended claims.

The invention herein described may be manufactured and used by or for the Government of the United States of America for governmental purposes without the payment of any royalty thereon or therefor.

What I claim as new and desire to secure by Letters Patent of the United States is as follows:

1. A demountable electron discharge device comprising a cylindrical anode forming a vacuum chamber, a plurality of elements including a filament disposed in said chamber, chuck grips mounted adjacent opposite ends of said chamber for removably supporting said filament in position and permitting removal of and renewal thereof, spring means forming an integral part of said device for maintaining said filament in tension at all times, and means for directing a fluid over the inner surfaces of a portion of said filament chucks and over the outer surface of a portion of said anode.
2. A demountable electron discharge device comprising a cylindrical anode forming a vacuum chamber, closure members for each end of said chamber, a plurality of elements including a filament disposed in said chamber, said filament being formed by a single straight wire mounted centrally of said device and supported at either end by chuck grips carried by said closure members, spring means interposed between one of said closure members and one of said chuck grips for automatically maintaining tension on said filament, means for fluid cooling said chucks and said cylindrical anode, and means for evacuating the space in said chamber between said anode and said filament.
3. A demountable electron discharge device comprising a cylindrical anode forming a vacuum chamber, a plurality of elements including a filament disposed in said chamber, metallic end plates extending laterally of said chamber adjacent each end of said anode and insulated with respect thereto, said filament being formed by a single straight wire mounted centrally of said device and supported at either end by chuck grips supported by said metallic end plates, said metallic plates constituting the filament terminals, said cylindrical anode constituting the body of the device intermediate said metallic end plates, means for fluid cooling said chucks and said anode, and means establishing connection of the device to a vacuum pump.
4. A demountable electron tube comprising a cylindrical plate electrode, an insulated sleeve engaging opposite ends of said cylindrical plate electrode, a pair of end members, tension devices interconnecting said end members, means for sealing said insulated sleeves with respect to said cylindrical plate and said end members for establishing a closed chamber within said cylindrical plate, a grid electrode extending through said chamber, a chuck device carried by each of said end members, a filament extending axially of said chamber and removably mounted at the ends thereof in said chuck device, and means for establishing a vacuum in said chamber.
5. A demountable electron tube comprising a cylindrical plate electrode, an end member insulatingly supported with each end thereof, means for drawing said end members together under tension for forming a substantially closed chamber within said cylindrical plate electrode, a grid electrode supported within said chamber, a chuck carried by each of said end members and expandable and contractible for removably receiving the opposite ends of a filament electrode.
6. A demountable electron tube comprising a cylindrical plate electrode having a central fluid cooled portion and cylindrical end portions, an insulated sleeve concentrically disposed about
- each end of said cylindrical plate electrode, end members disposed laterally of each of said insulated sleeves, tension members interconnecting said end members for compressing said end members against said insulated sleeves, gaskets interposed between said insulated sleeve, said end members and said cylindrical plate electrode for establishing a substantially airtight chamber within said cylindrical plate electrode, a grid electrode mounted within said chamber, an expandable and contractible chuck carried by each of said end members, a filament electrode having its opposite ends removably gripped by each of said chucks, and means for establishing a vacuum in said chamber.
7. A demountable electron tube comprising a cylindrical plate electrode, attachable cover members insulatingly supported across each end of said cylindrical plate electrode, tension members for compressing said cover members toward the ends of said cylindrical plate electrode, means for establishing a substantially airtight chamber within said cylindrical plate electrode, a grid electrode mounted concentrically within said chamber, an expandable and contractible chuck member carried by each of said cover members, a filament wire having its opposite ends removably gripped by said chucks, and means for establishing a vacuum within said chamber.
8. A demountable electron tube comprising a cylindrical plate electrode, a sleeve of insulation material engaging each end of said cylindrical plate electrode, a plate member extending normal to each of said insulated sleeves, gaskets disposed between said cylindrical plate electrode and said insulated sleeves, gaskets disposed between said insulated sleeves and said end members, tension means interconnecting said end members for compressing said end members, said gaskets and said insulated sleeves with respect to the ends of said cylindrical plate electrode for forming a substantially airtight closure, a grid electrode supported from one of said end members and extending concentrically within said cylindrical plate electrode, an expandable and contractible chuck supported by each of said end members, a wire-like filament extending axially with respect to said cylindrical plate electrode and removably engaged at its opposite ends in said chucks, and means for exhausting and maintaining a vacuum within said closure.
9. A demountable electron tube comprising a cylindrical plate electrode having a double wall portion centrally thereof and a single wall extension on each end thereof, an insulated bushing concentrically disposed about each of said extensions, an end plate extending across each of said insulated bushings, gaskets disposed between said cylindrical plate electrode and said insulated bushings, gaskets disposed between said insulated bushings and said end plates, means for compressing said end plates against said gaskets and insulated bushings for providing a substantially airtight closure, a grid electrode insulatingly supported from one of said end members and disposed centrally within said cylindrical plate electrode, an expandable and contractible chuck supported by each of said end members, a filament having its opposite ends engageable by said chucks and extending axially of said cylindrical plate, and means for establishing a vacuum within said closure.
10. A demountable electron tube comprising a closure member, end plates for said closure mem-

- ber, means for compressing said end plates against said closure member and establishing a substantially airtight connection therewith, an expansible and contractible chuck supported from 5 each of said end plates, a filament extending axially through said closure member and having the ends thereof removably engageable by said chucks, and means for evacuating said closure member.
- 10 11. A demountable electron tube comprising a closure member, end plates for said closure member, means for compressing said end plates against said closure member and establishing a substantially airtight connection therewith, an expansible and contractible chuck supported from each of said end plates, a filament extending axially through said closure member and having the ends thereof removably engageable by said chucks, each of said chucks including a hollow bore extending centrally thereof for receiving a cooling fluid and being screw threaded on the exterior thereof for receiving an adjustable sleeve for clamping or releasing said chucks with respect to said filament.
- 15 12. A demountable electron tube comprising a closure member, end plates for said closure member, means for compressing said end plates against said closure member and establishing a substantially airtight connection therewith, an expansible and contractible chuck supported from each of said end plates, a filament extending axially through said closure member and having the ends thereof removably engageable by said chucks, each of said chucks having a hollow internal bore 20 extending axially thereof, a fluid inlet port adjacent the clamping end of each of said chucks and a fluid discharge port remote from the clamping end of said chucks.
- 25 13. A demountable electron tube comprising a tubular closure member, end plates extending laterally with respect to each end of said tubular closure member, insulation means for insulatingly mounting said end plates with respect to the ends of said closure member, tension means for 30 compressing said end plates and said insulation means with respect to the ends of said tubular closure member for providing a substantially airtight chamber within said tubular member, an expansible and contractible chuck supported by 35 each of said end plates, a grid electrode concentrically disposed about said chucks within said chamber, a filament having its opposite ends re-
- movably engaged in said chucks and extending axially of said chamber, means for fluid cooling each of said chucks, and means for establishing a vacuum within said chamber.
- 40 14. A demountable electron tube comprising a cylindrical anode, means telescopically engaging opposite ends of said anode, closure members disposed adjacent said means for providing a substantially airtight chamber within said cylindrical anode, an expansible and contractible chuck disposed centrally in one of said closure members, means for resiliently supporting an expansible and contractible chuck in the other of said closure members, a filament removably connected at each end thereof in said chucks, each of said 45 chucks having a hollow bore extending longitudinally thereof, a fluid inlet tube projecting into the said hollow bore to a position adjacent the clamping end of said chuck, and a fluid discharge connection at the end of said bore remote from the clamping end of said chuck.
- 50 15. A demountable electron tube comprising a tubular chamber, a removable end closure for each end of said chamber, a corrugated diaphragm mounted centrally of one of said end closures, an 55 expansible and contractible screw chuck mounted in said corrugated diaphragm, an expansible and contractible screw chuck carried by the other of said removable end closures, a grid electrode supported by said last mentioned end closure, and a 60 filament having its opposite ends engaged by said screw chucks and extending axially through said tubular chamber.
- 65 16. A demountable electron tube comprising a tubular chamber, a removable end closure for 65 each end of said chamber, an expansible and contractible screw chuck mounted in one of said removable end closures, a corrugated diaphragm disposed centrally of the other of said removable end closures, a pair of tension members disposed in spaced relation to said corrugated diaphragm, an expansible and contractible screw chuck carried by said corrugated diaphragm and engaged by said pair of tension members, and a filament having its opposite ends removably engaged in said expansible and contractible screw chucks, said pair of tension members operating to advance or retract the screw chuck connected therewith for maintaining said filament taut under conditions of expansion due to varying temperatures.

LOUIS A. GEBHARD,
